UNITED STATES PATENT OFFICE

2,545,175

CONTROL VALVE FOR DEEP WELLS

Orville R. Stump, Long Beach, and Arthur W. Titus, Whittier, Calif.

Application November 18, 1947, Serial No. 786,722

4 Claims. (Cl. 103—227)

1

Our invention relates to means for closing at the bottom the tubing of a well for oil or other subterranean fluid.

During such operations as withdrawing or running in the sucker rods or the tubing, it is necessary to prevent the flow of gas, oil, or both from the well into the open air. It is troublesome and not entirely practicable to maintain the upper end of the tubing string closed during such operations; in handling the rod string, the size and shape of the string at and adjacent the couplings makes it difficult to maintain a good seal between the tubing and the rods, and in handling tubing it adds materially to the labor to remove and insert a plug every time a stand of tubing is coupled or uncoupled. Furthermore, during the coupling or uncoupling of tubing the tubing string is unavoidably open for a short time.

In the past it has been a frequent practice to "kill" a well by pumping in mud or water before pulling the tubing, in order to avoid the difficulties inherent in shutting off flow at the well head. But it has been found that wells seldom if ever recover full productivity after such treatment.

An object of our invention is to provide a valve capable of closing the lower end of a tubing string at times when such closure is desired, but capable of being maintained open during productive operation of a well.

Further objects and advantages of our invention will appear from the following description and from the drawing, in which:

Fig. 1 is a sectional view illustrating our apparatus in place in a well; and

Fig. 2 is a view in elevation illustrating a device for maintaining the valve open during a well's period of free flow.

Referring to Fig. 1 of the drawing, 10 represents a casing or liner, connected by collar 11 to slotted pipe 12 which is located in the productive portion of a well. Suspended within the casing is a tubing string the lowermost end of which is indicated at 13. A bottom lock shoe, consisting of the three elements 14, 15, and 16, is affixed to the lower end of the tubing.

Pump mandrel 17 is the lower extension of the working barrel of a deep-well pump fitting within the tubing. The mandrel is provided with a seating bevel 18 and with a hold-down consisting of dogs 19—19 and springs 20—20, adapted to engage the bottom lock shoe to inhibit vertical motion of the pump mandrel and members affixed thereto.

The foregoing elements are all conventional and

2

may take any of the numerous forms customary in wells having rod pumps with working barrels anchored to the tubing, including forms in which the hold-down is situated near the top of the working barrel instead of in the bottom mandrel.

Valve body 21 is a cylindrical member threaded internally at each end and provided with internal shoulders facing each end. The upper shoulder receives valve-seat ring 22 which is held in place by collar 23. A centering guide consisting of tube 24 and a plurality of radial legs 25—25 is mounted within valve body 21, the ends of the radial legs fitting against the lower shoulder of valve body 21 and being held in position by threaded nipple 26.

Valve stem 27, which is slidably fitted within tube 24, carries valve 28 at its upper end. A helical spring 29 is mounted between valve 28 and radial legs 25—25, to urge the valve upwardly into contact with valve-seat ring 22.

Collar 23 is connected with the lower element 16 of the bottom lock shoe by nipple 30, and lower nipple 31 is connected at 31 with a tail pipe, a gas anchor, or any other desired equipment.

At the lower end of pump mandrel 17 is affixed a perforated mosquito-bill 32, of sufficient length to reach valve 28 and to hold the valve open when the pump is seated, that is, when bevel 18 is in contact with the upper bevel of ring 15 and dogs 19—19 are engaging the lower bevel of ring 15.

Fig. 1 illustrates the valve in closed position and the pump mandrel a little above the seated position. When the rod string is lowered sufficiently to force the pump into seated position, valve 28 is opened and it remains open as long as the pump is operating. But, when the rod string and the attached pump are withdrawn from the well, valve 28 closes as soon as the pump is unseated. As a result, during the entire time that it is necessary or convenient to have the tubing string open at its upper end, flow of gas and oil through the tubing is inhibited by a bottom closure.

When the tubing itself is pulled or run into the well, the closure at the bottom of the string makes unnecessary the troublesome and inadequate procedure of plugging the upper end of the tubing string each time a stand of tubing is coupled or uncoupled.

It is entirely practical to install our bottom-hole valve in a new well, when the tubing is first run into the well and before the drilling mud has been circulated out of the hole. However, in cases where the well is to have a period of

free flow before going on the pump, it is necessary to provide a substitute for the pump anchor in the means for maintaining the valve open during productive operation of the well. A device for this purpose is illustrated in Fig. 2.

Anchor 117 is, in its lower portion, the same in structure as pump mandrel 17 of Fig. 1, and it is similarly equipped with elastically mounted hold-down dogs 119—119 shaped and arranged to engage bottom-lock-shoe ring 15 of Fig. 1. The upper portion of anchor 117 is provided with apertures 133—133, to permit flow of oil or other well fluid, and is surmounted by stub 134 which serves as a handle to be grasped by a fishing tool. Perforated mosquito-bill 132, identical or equivalent to element 32 of Fig. 1, is affixed to the lower end of anchor 117 and serves to maintain valve 28 open while the anchor engages the bottom lock shoe.

When the tubing is originally run into the well, it is provided with whatever type of lock shoe or other anchor-engaging equipment that is required for the type of pump intended for eventual use in the well, and anchor 117 is provided with a hold-down matching that of the pump or at least capable of engaging the same tubing equipment.

Anchor 117 remains in place throughout the period of free flow, unless it is desired to withdraw the tubing or to change its setting during this period. Valve 28 is not necessarily closed during the operation of changing the setting of the tubing, as this work may not involve opening the tubing head long enough to justify a bottom closure. But it should be noted that the valve may close automatically if an extreme gas pressure is encountered during the operation; thus the valve cooperates with the conventional blow-out preventer at the well head to control the well in such an emergency.

When it is desired to pull the tubing or to run in a pump, the valve is closed by withdrawing anchor 117. Removal of the anchor involves the operation of running a fishing socket into the well without the benefit of a bottom closure, but this fact is of only minor importance. The fishing tool can be handled by a string of smooth-jointed pipe or rod or, in some cases, by a cable; so it is not difficult to maintain an efficient closure of the tubing at the well head. If desired, anchor 117 can be affixed to a cable or rod string which is left in the well, in order to eliminate the fishing operation.

We claim as our invention:

1. In a well provided with a tubing string, control means comprising: a valve body connected with the lower end of said tubing string and having a valve seat; a movable valve member mounted beneath said valve seat and arranged to close the passage into said tubing string by contact with said valve seat when at its upper limit of motion; resilient means urging said valve member upwardly toward said valve seat; an anchor fitting within said tubing and provided with hold-down means capable of engaging said tubing; and a member affixed to said anchor, arranged to bear upon said valve member and to hold said valve member away from said valve

seat while said anchor is in engagement with said tubing.

2. In a well provided with a tubing string and with a pump having a working barrel fitting within said tubing and anchored thereto, flow control means comprising: a valve body provided with a valve seat, said valve body being connected with the lower end of said tubing string beneath said pump; a movable valve member mounted beneath said valve seat and arranged to close the passage into said tubing string by contact with said valve seat when at its upper limit of motion; resilient means urging said valve member upwardly toward said valve seat; and a member affixed to the working barrel of said pump, arranged to bear upon said valve member and to hold said valve member away from said valve seat while said working barrel is anchored to said tubing.

3. In a well provided with a tubing string and with a pump fitting within said tubing, said pump having a part which remains stationary during normal operation of the pump, flow control means comprising: a valve body provided with a valve seat, said valve body being connected with the lower end of said tubing string beneath said pump; a movable valve member mounted beneath said valve seat and arranged to close the passage into said tubing string by contact with said valve seat when at its upper level of motion; resilient means urging said valve member upwardly toward said valve seat; and a member affixed to said normally stationary part of said pump, arranged to bear upon said valve member and to hold said valve member away from said valve seat while said pump is in operative position.

4. In a well provided with a tubing string, control means comprising: a valve body connected with the lower end of said tubing string and having a valve seat; a movable valve member mounted beneath said valve seat and arranged to close the passage into said tubing string by contact with said valve seat when at its upper limit of motion; resilient means urging said valve member upwardly toward said valve seat; an anchor fitting within said tubing and provided with hold-down means capable of engaging said tubing, said hold-down means being adapted to release when the upward force applied to said anchor exceeds a predetermined limit; and a member affixed to said anchor, arranged to bear upon said valve member and to hold said valve member away from said valve seat while said anchor is in engagement with said tubing.
